UNITED STATES PATENT OFFICE.

CLEMENS GRAAFF, OF BERLIN, GERMANY.

FIRE-EXTINGUISHING ARRANGEMENT FOR AERIAL CRAFT.

1,286,998.

Specification of Letters Patent. Patented Dec. 10, 1918.

Application filed February 13, 1915. Serial No. 8,024.

To all whom it may concern:

Be it known that I, CLEMENS GRAAFF, a subject of the German Emperor, and residing at Linkstrasse 17, Berlin, Germany, have invented certain new and useful Improvements in Fire-Extinguishing Arrangements for Aerial Craft, of which the following is a specification.

The present invention relates to a fire extinguishing arrangement for aerial craft. The arrangement consists essentially of a container for the extinguishing liquid with a gas generating attachment adapted to be opened from outside and several jet pipes branched from the said container. In motor driven air ships the container for the extinguishing liquid, made of a suitable size, is disposed at a suitable part of the craft. The container may also be made to communicate with several gas generators, so as to allow of increasing the pressure of the extinguishing liquid at will, or to allow of squirting repeated charges of the container. Within the reach of the driver of the craft one or several levers are provided for operating the gas generating attachment or attachments. From the container for the extinguishing liquid proceeds a system of either rigid or movable jet pipes, which are carried all over the air ship. In these pipes stop valves may be provided, which, if desirable, may also be controlled or operated from the driver's stand. In aeroplanes, likewise, a lever for operating the gas generating attachment, and the stop valve of a jet pipe leading to the carburetor of the motor and preferably provided with a spraying nozzle at its end are disposed within the reach of the aviator. A second jet pipe, preferably flexible, is also carried up to the aviator's seat. This second pipe preferably ends in a jet directing device which comprises a handle, a spraying nozzle, a stop valve and an operating lever extending over the handle, for controlling the said stop valve. Such jet directing devices may, besides, also be employed on the jet pipes on board motor driven airships. The whole arrangement will be more compact and simple, for use on aeroplanes, if a container for the extinguishing liquid, also containing a pressure gas generating attachment, is secured within the reach of the aviator to one of the posts of the aeroplane.

In the accompanying drawing the present

invention is exemplified in a constructional form for use on an aeroplane.

In the drawing *a* is the container for the extinguishing liquid, which is detachably secured by means of a suitable holder *b* with bracket *c* and clamp *d* to a post *e* of the aeroplane within the reach of the aviator. The charging mouth of the container *a* is surrounded within the latter by a tube or cylinder *f*, which prevents, in a known manner, the container from being completely filled, so that an air space will remain in the same when it has been charged. In the charging mouth of the container a gas generator *g* or the like is fitted. In the cap *h* of the mouth a percussion pin *i* is guided, which serves to open the gas generator *g*. On the neck *k* of the cap *h* is fitted a rotatable ring *m*, which has an arm *n*. To the latter is pivoted a lever *o* by means of which the pin *i*, which is under action of a spring *p*, may be operated. After the lever *o* has been set within the reach of the aviator, the ring *m* is secured to the neck *k* by means of a set screw *q* or the like.

Within the container *a* is disposed an outlet pipe *r*, to which are connected outside of the container two jet pipes *s* and *t*. The former is flexible and closed with a jet directing device comprising a handle *u*, a valve *v* with valve *w*, a hand lever for operating this valve and a jet nozzle *y*. This jet directing device likewise lies or hangs within the reach of the aviator. In the pipe *t* a cock or valve *z* is fitted. This pipe, which is similar to pipe *s* is readily detachable from its connection to container *a* and is preferably rigidly fitted and leads to the carburetor of the motor, where it terminates in a sprayer nozzle *l* of any suitable design.

In case of a fire in the carburetor the aviator will, by depressing the lever *o* of the gas generator *g* start the latter and open the valve *z*, whereupon a spray will emerge from the nozzle *l*, and immediately extinguish the fire. If a fire breaks out elsewhere on the air craft, the aviator will likewise open the generator *g*, then seize the jet directing device *u* and on depressing the lever *x* he will let the jet of extinguishing liquid emerge from the nozzle *y* and direct it against the fire.

I claim:

A fire extinguishing arrangement for aeroplanes consisting of a container for an

extinguishing liquid secured to a part of the frame of the said aeroplane and within easy reach of the aviator, a gas generator within said container, a cap closing said container, 5 a spring actuated lever for operating the gas generator, a ring bearing said lever and being rotatably mounted upon the neck of said closure cap, a set screw in said ring for securing it to the cap in a predetermined position and a branched pipe leading from 10 said container, one branch of said pipe connecting with a pipe containing a valve within reach of the aviator and terminating in

a spraying nozzle positioned adjacent the carburetor of the motor, the other branch 15 leading with a flexible hose to the aviator's seat and terminating in a jet directing device comprising a handle, valve, valve operating lever and jet nozzle.

In testimony whereof I affix my signature 20 in presence of two witnesses.

CLEMENS GRAAFF.
